UNITED STATES PATENT OFFICE.

WILLIAM F. NEWTON, OF VALLEY VIEW, TEXAS.

COTTON-ELEVATOR.

SPECIFICATION forming part of Letters Patent No. 242,963, dated June 14, 1881.

Application filed March 30, 1881. (No model.)

To all whom it may concern:

Be it known that I, WILLIAM F. NEWTON, of Valley View, in the county of Cooke and State of Texas, have invented a new and Improved 5 Cotton - Elevator, of which the following is a specification.

The object of this invention is to facilitate the delivery of cotton to the gin, and at the same time to remove from the cotton the gravel 10 and other foreign substances that may be in it, thereby preventing injury to the gin and causing it to deliver the cotton in better and cleaner condition.

Figure 1 is a sectional side elevation of the 15 device on line $x x$, Fig. 2 is a front elevation of the same, partly in section. Fig. 3 is a plan of the same, partly in section, on line $y y$, Fig. 1.

Similar letters of reference indicate corresponding parts.

In the accompanying drawings, A represents the elevator - frame, consisting of two parallel sides, $A' A'$, set on edge, and held together by a central division, A^2 , that is placed 25 flatwise, as shown. Pivoted on each of these sides $A' A'$, at their upper ends, are standards B B, that support the device in position; or, in lieu of these standards B B, the elevator may have its top supported on a cross-beam or other 30 convenient substitute.

Journalized in the sides $A' A'$, near the top of the elevator, is the cross-shaft C, carrying a drum or roller, C', and the lower ends of the sides $A' A'$ are slotted, as shown at a , and 35 on either side of said slots a are secured strips b, between which slide the bearings D² of the lower shaft, D, carrying the lower drum or roller, D'. Pins are entered vertically through one of the strips b on either side and into the 40 edge of the bearing D² on that side, thereby holding said bearings D² in any desired position, said bearings D² being adjustable up and down to regulate the tension of the endless belt E. This belt E, which is drawn about 45 the drums C' D' between the frame-sides $A' A'$, is composed of two side strips, d, of leather or other suitable material, across which are laid and fastened by pins f slats g, of wood or other suitable material, and at regular intervals stouter slats h are interposed between the slats g, provided with outward-extending

spikes or sharp pins m, as shown, which are designed to catch and carry the cotton upward when the elevator is in operation. Beneath the upper part of the belt E strips n are fastened on the inside of the sides $A' A'$, to prevent the sagging of this part of said belt E, and beneath the under part of the belt E strips o are fastened on the sides $A' A'$, to prevent the sagging of this portion of the belt E. Rolls 55 or sheaves F, fixed on a shaft, F', which is journaled in slots p in the lower edge of the sides $A' A'$, serve as further support to the belt E.

Fastened between the sides $A' A'$, below 60 the lower end of the belt E, is a semicircular pan or receiver, G, designed to catch the gravel and other foreign substances that may fall from the cotton as it is elevated.

Secured upon the face of the frame A, near 65 the bottom thereof, with its bottom just above the receiver G, is a hopper, H, designed to be of sufficient capacity to hold a bale or cart-load of cotton in the seed; and extending across the hopper H is a bar, t, to prevent the cotton from 70 being crowded down through the opening s in the said hopper H upon the belt E. Through this opening s the foreign substances in the cotton will fall into the receiver G, the spikes m', protruding inward from the lower part of 75 the hopper H, preventing the cotton from falling into said receiver G. The straight sides u of the hopper H permit the cotton passing through said hopper H to turn, thereby forming a roll similar to that formed in the gin-breast. 80

On the outer end of the shaft C is a driving-pulley, I, and journaled in the top of the elevator-frame A is a cross-shaft, K, carrying a cylindrical brush, L, and having its pulley K' 85 bearing against the inside of the driving-pulley flange, whereby said brush L is revolved in the same direction as the said driving-pulley I. This brush L, as it revolves, removes the cotton from the spikes m as they come in 90 successive rows to the top of the elevator.

This elevator can be made of any desired length, and be placed at any convenient angle, and be attached to any gin-feeder now in use, or be used successfully without a gin-feeder 95 to deliver cotton to the gin, thereby leaving more room on the floor where the gin-stand is

set, and leaving more room for access to the gin-breast and other parts of its machinery.

The elevator may be run from a shaft with a slack belt and tightener, or in any other 5 convenient manner.

I am aware that it is not new to use an endless slat-belt with spikes or hook-teeth, or, in connection therewith, a frame carrying a hopper, chute, and a door at the lower end; but 10 What I claim as new and of my invention is—

1. In a cotton-elevator, the combination, with an endless slat-belt having transversely-arranged spikes m , of the pan G at the lower

end, and the hopper H , having spikes m' below 15 its hole S , whereby the cotton is prevented from falling into the pan, while the dirt and gravel are allowed to do so, as described.

2. In a cotton-elevator, the hopper H , constructed, substantially as herein shown and 20 described, with cross-bar t , straight sides u , and spikes m' , as and for the purposes set forth.

WILLIAM FREDERICK NEWTON.
